UNITED STATES PATENT OFFICE.

ROBERT ZAHN, OF PLAUEN, GERMANY; ALFRED RIETZSCH ADMINISTRATOR OF SAID ZAHN, DECEASED.

TAKE-UP MECHANISM FOR EMBROIDERING-MACHINES.

1,108,418.

Specification of Letters Patent.

Patented Aug. 25, 1914.

Application filed January 25, 1913. Serial No. 744,206.

To all whom it may concern:

Be it known that I, ROBERT ZAHN, a subject of the German Emperor, residing at Plauen, in Vogtland, in the Kingdom of Saxony, Germany, have invented certain new and useful Improvements in Take-Up Mechanism for Embroidering-Machines, of which the following is a specification.

In the hitherto known shuttle embroidering machines in which opposite each shuttle two alternately operating rows of needles are provided which enable embroidering either with threads of different character or of different colors, there is the drawback that the two thread take up devices must necessarily be arranged at a considerably far distance apart from one another in order that the movements of one device be not interfered with by those of the other. Because of such construction the available space in which the machine is installed and which is measured in the direction from the front to the rear is disadvantageously reduced, the stand for the attendants in front of the machine excessively removed from the fabric rendering it difficult for the attendants to reach the latter with their hands, and furthermore the length of the part of the thread extending from the fabric to the thread take up devices becomes uneven.

The object of this invention is to remove the drawback above referred to and is accomplished by improving the construction and arrangement of the thread take up levers in such a manner that the latter crossing one another permit the group of take up levers for one needle row during their operation to come into the range of the other group.

My invention is more or less diagrammatically illustrated in the accompanying drawing in which so much of the embroidering machine is shown as is necessary for the full understanding of the construction and operation of the new device.

In the drawing similar reference characters denote corresponding parts and Figure 1 is a side view of the embroidering machine and of my new device; Fig. 2 is a front view of the new device.

x—x denotes the plane of the fabric and *a* and *b* denote the bars for the two needle groups. These bars in well known manner are so arranged that those of one group are

capable of reciprocating through the spaces between the bars of the other group. In the position shown in Fig. 1 the needles secured to the bar *a* of one group are in operative position penetrating the fabric, while the needles secured to the bar *b* of the other group are withdrawn and out of operation.

f and *k* denote the thread spools, *e* and *i* guide rolls for the threads, *h* is a rail fixed to the machine frame having a rounded edge *h'*, *d* denotes the small thread take up lever and *c* and *g* the large take up levers. These large take up levers or arms *c* and *g* are respectively secured to spindles *m* and *n* suitably borne in the machine frame and are punched and pressed from sheet metal, so as to have hook shaped and rounded ends or heads *c'* and *g'*. On the sides each hook shaped end or head *c'* and *g'* is provided with fingers or projections *o*. The threads for the needles of bar *a* are each conveyed from the spool *f* over the guide roll *e*, over the small take up lever *d*, then over the rounded surface of the hook shaped end *c'* of the lever *c*, between the fingers *o* thereof, to the needle, and the threads for the needles of bar *b* are each conveyed from the spool *k*, over the guide roll *i*, the rounded edge *h'* of the rail *h*, the small take up lever *d*, the rounded surface of the hook shaped head *g'* of the lever *g* between the fingers *o* thereof to the needles. Because of the peculiar shape of the levers *c*, *c'* and *g*, *g'* and the arrangements thereof shown in Fig. 2, the two groups of levers *c* and *g* are capable of overlapping without interfering with one another.

What I claim and desire to secure by Letters Patent is:

1. In an embroidering machine, the combination with groups of needles for carrying different threads, of a secondary take up mechanism and groups of primary take up mechanisms, one for each group of needles, said primary take up mechanisms comprising spindles arranged eccentrically parallel and adjacent to one another and primary take up levers secured to said spindles, whereby the different groups of primary take up mechanisms during operation without interference can overlap one another.
2. In an embroidering machine, the combination with groups of needles for carrying different threads, of a secondary take up mechanism and groups of primary take up

mechanisms, one for each group of needles, said primary take up mechanisms comprising spindles arranged eccentrically parallel and adjacent to one another and primary ⁵ take up levers secured to said spindles and each having a rounded hook-shaped head and lateral guide fingers on said head.

In testimony whereof I affix my signature in presence of two witnesses.

ROBERT ZAHN.
